UNITED STATES PATENT OFFICE.

E. BRUCE PRESTON, OF CHICAGO, ILLINOIS.

DESIGN FOR A RUBBER BOOT OR SHOE.

SPECIFICATION forming part of Design No. 16,678, dated May 4, 1886.

Application filed March 20, 1886. Serial No. 190,035. Term of patent 7 years.

To all whom it may concern:

Be it known that I, E. BRUCE PRESTON, a citizen of the United States, residing in Chicago, in the county of Cook and State of Illinois, have invented a new and original Design 5 for Rubber Boots or Shoes, of which the following is a specification.

This invention is intended to be applied to the uppers of rubber boots or shoes; and it 10 consists of a series of rings and radiating arms upon the surface of such uppers, resembling in appearance a spider's web.

The design is shown in the annexed drawings as applied to an overshoe, Figure 1 being 15 a side elevation, and Fig. 2 a plan, thereof.

In said drawings, A represents the "upper," as it is commonly called, of a shoe or boot, and

my design is formed upon the front thereof, as clearly shown.

The design is made up of a series of rings, 20 b b, and arms d, crossing said rings in directions radiating from e as a center, said rings and arms forming a labyrinth of lines or ribs, much resembling a spider's web.

I claim—

The design herein shown and described for the upper of a rubber boot or shoe, the same consisting of rings and radiating arms on the surface of the upper in conventional representation of a spider's web.

E. BRUCE PRESTON.
